UNITED STATES PATENT OFFICE

HARRY W. MILLER, OF LANCASTER, PENNSYLVANIA

GRINDING MACHINE

Application filed August 29, 1931. Serial No. 560,173.

My invention relates to grinding machines and especially to grinding machines particularly designed for sharpening the curved blades of lawn mowers.

5 The object of my invention is to provide in a grinding machine for sharpening lawn mower blades, improved means for driving and reciprocating the grinding tool. A further object of my invention is to provide, in 10 a device of the class mentioned having a reciprocating carriage for the grinding element, a single driving element carried by the carriage and geared to drive the driving element and to reciprocate the carriage. A 15 further object of my invention is to provide improved means for reversing the carriage at the end of each reciprocation. A further object of my invention is to provide safety means for preventing the carriage from traveling too far in either direction and at the same time to maintain the reciprocating mechanism in operative geared connection. A further object of my invention is to provide 20 improved carriage reversing mechanism which shall be easily actuated and of such construction as to prevent locking or jamming of the gears. A further object of my invention is to provide improved means for maintaining the mower blade in proper 25 relation to the grinding tool. A further object of my invention is to provide, in a device of the class mentioned, means for maintaining the mower blade in proper relation to the grinding tool, said means being adjustable, vertically, horizontally and angularly 30 to accommodate various types and sizes of mowers. A further object of my invention is to provide, in a machine of the class mentioned, means for maintaining the blade in proper relation to the grinding tool and of such construction that blades may be sharpened when so badly worn as to project but slightly beyond their supporting arms. Other objects will appear hereinafter.

45 With these objects in view my invention consists generally in a grinding tool comprising a reciprocatory carriage mounted upon ways, a rack bar paralleling said ways, a grinding tool on said carriage, a motor mounted on said carriage, gearing connect-

ing the motor and grinding tool and a train of gearing connecting the motor and said rack bar for reciprocating the carriage, whereby the carriage is reciprocated at a slow speed and the grinding tool driven at a high speed, simultaneously from the same motor. My invention further consists in a device as above mentioned, in which the train of gears for reciprocating the carriage includes a pair of oppositely rotated pinions 40 adapted to be alternately engaged with a pinion in mesh with the rack for imparting reciprocatory motion to the carriage. My invention further consists in a device as above mentioned, including a worm gear connection between the motor shaft and the train of gears for stepping down the speed of the carriage reciprocating gearing. My invention further consists in a device as mentioned in combination with adjustable means for 45 automatically shifting the rack engaging pinions at the end of each reciprocation.

50 My invention further consists in a device of the class mentioned including a reciprocatory carriage; a rack and pinion for reciprocating the same, in which the rack is floating, that is, mounted to have a limited longitudinal movement, and of such length as to be disengaged by the pinions at the extreme limits of movements; and resilient means for returning the rack bar to position to engage with the pinion to facilitate reversal of travel of the carriage. My invention further consists in a device of the class under consideration including a reciprocatory carriage, a 55 rack, a pinion on the carriage meshing with said rack, a pair of oppositely driven pinions mounted on a pivoted member carried by said carriage and means for automatically shifting said member at the end of each reciprocation of the carriage to mesh the alternate pinions with the first said pinion, the direction of rotation of said pinions and their relative positions being such as to maintain the same in mesh. My invention further 60 consists in a device as above stated further characterized by stops to limit the movement of the shifting gears to prevent the same from becoming jammed.

65 My invention further consists in a grind-

ing tool of the class mentioned including the grinding wheel and means for maintaining the lawn mower blade in proper relation thereto, said means comprising a fixed roller 5 and a roller mounted upon a swinging arm, the rollers being adapted to grip the blade upon opposite sides, and the last mentioned roller being adapted to be swung upwardly out of operative position when the tool is 10 operating upon a badly worn mower blade, so that the roller will not engage the reel arm which supports the blade. My invention further consists in a blade guiding device as mentioned, which may be vertically, horizontally and angularly adjusted with relation to the grinding tool so as to accommodate the device to mowers of different sizes. My invention further consists in various details of construction and arrangements of 15 parts, all as will be fully described herein-after and particularly pointed out in the claims.

My invention will be more readily understood by reference to the accompanying 20 drawings, forming a part of this specification and in which—

Figure 1 is a front elevation of a lawn mower grinding machine embodying my invention,

Fig. 2 is a transverse section of the same on substantially the line 2—2 of Fig. 1 and illustrated upon an enlarged scale, the vertical elements of the frame and adjacent parts being broken away,

Fig. 3 is a plan view of the device on an enlarged scale, partly broken away,

Figs. 4 and 5 are detail views illustrating the construction and manner of mounting the floating rack bar at one end,

Fig. 6 is a detail view illustrating the other end of the rack bar and associated parts,

Fig. 7 is a side elevation of the grinding wheel and associated parts illustrated upon a much enlarged scale,

Fig. 8 is a top plan view of the same,

Fig. 9 is a section on substantially the line 9—9 of Fig. 7, and

Fig. 10 is a detail of a portion of the work rest.

The device comprises broadly a rigid frame which includes the ways for a reciprocating carriage; a reciprocating carriage mounted on the ways, and carrying a motor, a grinding tool, and carriage driving gearing; a rack bar mounted upon the frame and associated with said gearing; adjustable means for automatically shifting the gearing; and adjustable work holding means.

The frame comprises a pair of similar skeleton end members 1 and 2 respectively connected at their lower ends by a pair of transverse members 3 and at their upper end by a longitudinally disposed bar 4. The bar 4 constitutes ways for the reciprocating carriage hereinafter described, and in order that

said carriage may be firmly supported on the single member 4, said member is made rectangular in cross section and arranged on its diagonal axis as clearly illustrated in Fig. 2 of the drawings. The ends of the member 4 are rigidly secured to the upper portion of the frame in any preferred manner.

The reciprocating carriage per se comprises upper and lower plates 5 and 6 secured together as by bolts 7 and recessed in their adjacent faces, as at 8, to snugly fit the ways 4. 9 indicates a motor casing secured to the underface of the carriage. This casing is provided on its upper portion with front and rear securing flanges 10 and 11 respectively, and the under member 6 of the carriage is formed with depending portions 12 and 13 to which said flanges are respectively secured.

14 indicates the motor shaft having suitable bearings in the motor casing and provided at one end with a worm 15 which meshes with a worm gear 16 in a shaft 17. The upper end of the shaft 17 is provided with a pinion 18 which is connected through a train of gears, hereinafter described, to a gear 19 which meshes with a rack 20 on a rack bar 21 mounted on the frame of the machine in a manner hereinafter described.

This gearing and rack are for the purpose of reciprocating the carriage on its ways. The worm and gear, 15—16, are arranged in a housing 22 at one end of the motor casing 9, and mounted upon the upper end of the housing 22 is a rearwardly extending fixed arm 23. Upon the end of said arm is secured a slide block 24, which engages the rear portion of the rack bar 21 and maintains a fixed distance between the rack bar and the shaft 17.

Pivotedly mounted on the upper face of the arm 23 is a bell crank lever 25 having a long arm 26 and a short arm 27, upon the ends of which are mounted pinions 28 and 29 respectively. The shaft 17 forms a pivot pin for the bell crank lever and by shifting said lever either of the pinions 28 or 29 may be brought into mesh with the gear 19. The pinion 29 is constantly in mesh with the pinion 18, whereas an idler 30 is interposed between the pinions 18 and 28. By this arrangement, the pinions 28 and 29 are constantly driven in opposite directions, so that by shifting the same to alternately engage the gear 19, the carriage will be driven in opposite directions. The arms 26 and 27 are of sufficient length whereby the teeth of the pinions 28 and 29 may be easily brought into and out of mesh with the gear 19. The bell crank lever 25 is provided with a forwardly extended arm 31, by means of which said lever and the pinions carried thereby may be shifted, either by hand or automatically in a manner hereinafter described.

In order to prevent injury to the motor, the

gearing, or other portions of the machine, should the gears not be properly shifted at the end of the travel of the carriage, I provide safety means for stopping the travel of 5 the carriage; and this includes means whereby the rack 20 and gear 19 are maintained in operative relation so as to return the carriage when the gears are shifted. To this end, the rack bar 21 is supported at its ends 10 in housings 32 and 33 arranged at the opposite ends, respectively, of the machine, and has limited longitudinal movement. The rack 20 is of but sufficient length to give the maximum desired travel to the carriage, so 15 that when the carriage reaches the extreme limit of its normal movement in either direction, the gear 19 passes slightly beyond the teeth of the rack. Without provisions being made to maintain the rack and gear in opera- 20 tive position, this travelling of the gear beyond the ends of the rack would prevent the return of the carriage in the opposite direction without considerable difficulty in again getting the rack and pinion into proper en- 25 gagement. In order to overcome this objection and maintain the rack and pinion in operative relation, I provide means for returning the rack into engagement with the gear after the gear has passed beyond the 30 ends of said rack. To this end, I provide adjacent each end of the rack, a plunger 34, slidably mounted in a lug 35 on the rack bar 31. Interposed between the lug 35 and the head of the plunger 34 is a spring 36. In 35 operation, when the carriage is travelling in one direction, the gear 19 will force the rack in the opposite direction for the limited movement of the rack bar, until the end of the bar engages a stop, such as the adjacent 40 portion of the frame 1 or 2. When the gear 19 passes from the opposite ends of the rack, the arm 23 on the gear housing engages the plunger 34 and forces the same toward the lug 35 against the tension of the spring 36. 45 The spring 36 will then move the rack bar and rack so as to maintain the end of the rack in operative relation with the gear 19 until the direction of rotation of said gear is changed by shifting the pinions 28 and 29. 50 In order to automatically shift the gears and adjust the length of travel of the carriage to suit the work, I provide adjustable stop members 36' arranged in the path of the arm 31. These stop members are prefer- 55 ably depending elements loosely mounted on a transverse shaft 37 and held in adjusted position by collars 38, adjustably fixed to the shaft 37 by set screws 39.

The opposite end of the motor shaft 14 60 from the worm 15 is provided with a spur gear 40, meshing with a pinion 41 on the shaft 42 of the grinding wheel 43. The gear 40 and pinion 41 are proportioned to step up the speed of the grind wheel 43. It will thus 65 be seen that the single motor shaft is geared

to drive the grinding wheel at a high speed and also geared to drive the carriage recipro- cating gearing at a low speed.

The mower is supported below the grinding wheel in the following manner. At the rear of the machine is a transverse longitudinal bar 44 upon which is slidably mounted a sleeve 45 having an upwardly projecting supporting lug 46 provided with a recess 47 in which the wooden roller of the lawn mower is adapted to rest at substantially its longitudinal center. The bar 44 is supported adjacent its ends by depending rods 48 which extends through apertures in the bar and are threaded as shown clearly in Figs. 1 and 2 to receive thumb nuts 49 upon which the bar 44 rests. By turning the thumb nuts 49, the height to the bar and the roller rest thereon may be adjusted. At each end of the device, are forwardly extending arms 50, the inner ends of which are provided with sleeves 51, whereby they are slidably mounted upon vertical ways 52. The arms are also provided with sleeves 53 through which are threaded vertical shafts 54. These shafts have their lower ends mounted at the base of the frame and their upper ends are journaled in the top of the frame, extended therethrough and equipped with bevel gears 55, which mesh with bevel gears 56 on the longitudinal shaft 37. The end of the shaft 37 is provided with a hand crank 57. It is obvious that by turning the shaft 37, the arms 50 will be simultaneously raised or lowered. Mounted upon each of the arms 50 is a slide 58 and the slides 58 are connected by horizontal members 59 spaced to provide a slot 60. Mounted on the members 59 are a pair of upwardly projecting sleeves 61 into which telescope rest members 62 adapted to support the cross bar of the mower, said members being recessed at their upper ends as at 63 for this purpose. The rest members 62 are adjusted vertically by means of a screw 64 threaded through the lower end of the sleeve 61. The lower ends of the sleeve 61 are reduced in diameter to extend through the slot 60 and are threaded to receive a nut 65 for clamping the sleeve in adjusted position on the members 59. By this construction, it is obvious that the mower after having been placed on the rest 46 and 62 may be nicely adjusted into proper relation to the grinding wheel 43.

The upper portion of the grind wheel 43 is covered by a suitable guard. This comprises a hollow substantially semi-circular member 66, which is mounted upon the outer face of the gear housing 67 which is provided on the end of the motor housing 9 for the gearing 40, 41. To this end, the gear housing 67 is formed with a lug 68, and the guard 66 with a similar lug 69, which are secured together in any preferred manner as by bolts 70.

One of the features of the present invention is improved means for maintaining the

curved mower blade in operative position relative to the grinding wheel 43. This comprises broadly a pair of rollers mounted upon each side of the grinding wheel adjacent its periphery, each pair being mounted upon a spring arm, and the outer roller of each pair being also mounted upon a pivoted member whereby it may be swung toward and from a companion roller. The rollers of each pair are adapted to engage opposite sides of the blade being sharpened and the pivotally mounted roller is held in yielding contact therewith by a suitable spring; and means are provided for adjusting the movement of this roller toward the fixed companion roller. Means are also provided for adjusting each pair of rollers vertically, horizontally and angularly with relation to the grinding wheel. As the pairs of rollers on each side of the grinding wheel and their associated parts are substantially identical, the description of one pair will suffice; it being understood that in practice one pair of rollers is set forwardly with relation to the other according to the degree of curve of the mower blade.

Referring to the drawings, particularly Figs. 7, 8 and 9, 71 indicates what will be called the fixed roller, and 72 the pivotally mounted roller. The fixed roller is of conical form and mounted on a spring 73, which is angularly disposed so as to bring the outer portion of the roller into a substantially vertical position. The arm 73 is provided at its end with a bracket 74 in which the upper end of the roller axel is mounted, the lower end of the axel being secured in the end of the arm 73. The bracket 74 is formed with an upwardly extending disk portion 75 and a rearwardly extending arm 76 having an offset lug 77. Pivotally mounted as at 78 on the disk 75 is a similar disk 79 having a substantially tangentially extending arm 80, upon the end of which is mounted the roller 72. A spring 81 interposed between the arm 80 and the lugs 77 tends to normally draw the roller 72 toward the roller 71. A setscrew 82 threaded through the arm 80 impinges against the end of the bracket 74 to regulate the space between the rollers. After the mower has been placed in proper position upon the supports 47 and 63, one of the blades is turned under the arm 73 in the direction of the arrow 83 in Fig. 7. The blade will engage the underface of the end of the spring arm 73, raising the same and the rollers until the blade slips between the rollers, when the resiliency of the arm 73 will return the rollers to normal position, clamping the blade between them. Sometimes the mower blade is so badly worn that its edge extends but a slight distance beyond the arm of the reel. At such times, the blade supporting arm of the reel would lie in the path of the roller. When such is the case,

the mower is reversed on its supports so as to present said arms toward the front of the machine, and the arm 80 with the roller 72 is raised into the position shown in dotted lines in Fig. 7. This allows the roller 71 to travel against the forward face of the blade, and the roller 72 is held out of position where it would otherwise engage the arm on the rear face of the blade. Under such circumstances, the position of the rollers must be adjusted with relation to the grinding wheel in order to place the proper bevel on the blade.

In order to permit proper adjustment of the rollers for such purpose as mentioned in the last paragraph, and for mowers of different types and sizes, the spring arm 73 is mounted upon a block 84 in such a manner as to be longitudinally (horizontally) adjustable thereon and the block carrying said spring arm is mounted for vertical adjustment. Provision is also made for angular adjustment of the arm 73. The upper end of the spring arm is rebent, forming a portion 85, which is slotted as at 86 to receive a bolt 87, tapped into the block 84. A strap member 88 is fixed to the portion 85 and has an upturned rear end 89 in which is swiveled a screw 90, said screw being tapped into the block 84. It is obvious that by loosening the bolt 87 and turning the screw 90, the spring arm 73 and the rollers carried thereby will be horizontally adjusted, forwardly or rearwardly with relation to the grinding wheel, after which the bolt 87 is tightened to secure the same in adjusted position. The front end of the member 88 is bent forwardly and downwardly, and extending from the same is a rod 91, the end of which is threaded and extended through the arm 73. A nut 92 threaded thereon impinges against the bottom of the arm and by turning said nut, the arm 73 may be adjusted angularly with relation to the horizontal. The block 84 has an upwardly projecting arm 93, which slides vertically between parallel ribs 66' on the side of the guard 66. A bolt 94 extends through the arm 93 and a slot 95 in the guard 66 and is provided with a thumb nut 96, whereby the block may be clamped in vertically adjustable position. A vertically disposed screw 97 extends through a lug 98 on the guard 66 and is tapped into the arm 93. A sleeve 99 is interposed between the lug 98 and the head 100 of the screw to bring the head well above the guard. It is obvious that when the thumb nut 96 is loosened, the block 84 may be readily adjusted by the screw 99. When properly adjusted vertically the clamp screw 96 is tightened to hold it in position.

It should be noted that the single motor mounted on the carriage is used for simultaneously driving the carriage and operating the grinding tool, the driving or reciprocation of the carriage being at a relatively

slow speed and the grinding tool being driven at a relatively high speed. This is accomplished through the gearing above described connecting the motor shaft with the rack and pinion, and the step up gearing connecting the same motor shaft with the shaft of the grinding tool.

It should also be noted that with the particular gearing described as connecting the motor with the rack, that the direction of rotation of the gears will tend to hold the same in their operative relation, and the arms 26 and 27 of the bell crank lever 25 are provided with stops 26' and 27' to limit the throw of the arms and prevent jamming or locking of the gears. The lengths of these arms are also such as to facilitate throwing the gears into and out of mesh without becoming locked.

20 I claim:

1. In a grinding tool, a reciprocating carriage, a rack, a gear on said carriage meshing with said rack, a bell crank lever pivoted on the carriage, pinions on the arms of said lever and adapted to be alternately engaged with said gear, speed reducing gearing connecting said motor and said pinions, and speed increasing mechanism connecting said motor and said grinding tool, substantially as described.

2. A device as set forth in claim 1 in combination with means for shifting the bell crank lever at the end of travel of the carriage in each direction and means for limiting the throw of said lever, substantially as described.

3. In a device of the class described, a reciprocating carriage, ways for said carriage, a rack paralleling said ways, a motor and motor casing mounted upon the carriage, gear housing at one end of said casing, a grinding tool supported on said housing, speed step up gearing arranged in said housing and connecting the motor and driving tool, a gear housing at the opposite end of said casing, a shaft mounted in said housing, an arm extending from said housing, means on said arm engaging the back of the rack bar, a pinion on said arm meshing with the rack, a bell crank lever pivotally mounted on said arm and including a pair of angularly disposed arms, pinions mounted on said arms and adapted to be alternately engaged with said gear upon shifting of the lever, and gearing connecting the last mentioned shaft and said pinions for driving said pinions in opposite directions, substantially as described.

4. A device as set forth in claim 3 in combination with adjustable means for shifting said bell crank lever, substantially as described.

5. In a device of the class described, a reciprocating carriage, a grinding tool carried thereby, a rack, a pinion carried by said car-

riage and meshing with said rack, means for driving said pinion in opposite directions to reciprocate the carriage, said rack bar having limited longitudinal movement and resilient means carried by the rack bar and adapted to be engaged by a portion of the carriage as the pinion reaches the end of the rack and adapted to maintain operative relation between the rack and pinion, substantially as described.

6. In a device of the class described, a reciprocating carriage, a grinding tool on said carriage, means for supporting a lawn mower with its rotary blades in operative relation to said grinding tool, blade guiding means adapted to engage the blade and maintain the same in operative relation to the tool as the carriage is reciprocated, said blade guiding means comprising a pair of gripping rollers engaging the blade upon opposite sides, one of said rollers being swingingly mounted and normally projecting below the level of the other roller, substantially as described.

7. A device as set forth in claim 6 further characterized by a spring arm supporting said rollers.

8. In a lawn mower sharpening device, a reciprocating carriage, a grinding tool mounted on said carriage and means for maintaining a lawn mower blade in position to be operated upon said grinding tool, said means comprising a fixed roller and a swinging roller at the side of the grinding tool and adapted to hold the blade between them, and means for adjusting said rollers horizontally, vertically and angularly with relation to the tool, substantially as described.

9. A device as set forth in claim 8 in combination with means for maintaining the swinging roller in or out of operative relation with the fixed roller, substantially as described.

10. In a device of the class described, a reciprocating carriage, a grinding tool mounted thereon and means for driving said tool, in combination with means for maintaining a lawn mower blade in proper relation to the grinding tool, said means comprising an angularly disposed spring arm, a fixed roller on the end of said arm, a clamping roller pivotally mounted on said arm, and means for maintaining the swinging roller in either operative or inoperative relation to the fixed roller, substantially as described.

11. A device as set forth in claim 10 in combination with means for adjusting the angularity of the spring arm, substantially as described.

12. A device as set forth in claim 10 further characterized by a block upon which said spring arm is mounted, a slot and bolt connection between said spring arm and block providing horizontally adjusting

means for the arm and the rollers carried thereby, substantially as described.

13. A device as set forth in claim 10 further characterized by a block upon which the spring arm is mounted, a slot and bolt connection between the arm and block providing horizontal adjustment for the arm and the rollers carried thereby, and means for vertically adjusting said block, substantially as described.

14. A device as set forth in claim 10 further characterized by a block upon which the spring arm is mounted, there being a slot and bolt connection between said block and spring arm, means for vertically adjusting the block and means for angularly adjusting said arms, substantially as described.

In testimony whereof I have signed my name to this specification.
